UNITED STATES PATENT OFFICE

EARDLEY HAZELL, OF NEW YORK, N. Y., ASSIGNOR TO REVERE RUBBER COMPANY,
OF PROVIDENCE, RHODE ISLAND, A CORPORATION OF RHODE ISLAND

METHOD AND APPARATUS FOR THE MANUFACTURE OF FILAMENTARY MATERIAL

Application filed March 11, 1931. Serial No. 521,641.

This invention relates to the production of filamentary material of desired shapes from aqueous dispersions of rubber in a manner which is simple and economical and by means 5 of which the shape of the filament produced may be accurately controlled and regulated.

An object of the invention is to provide a process and apparatus for forming continuous filaments of rubber from aqueous rubber 10 dispersions. Another object is to provide means for forming continuous rubber filaments having any desired cross-sectional shape, more particularly filaments having cross sections the boundaries of which are 15 straight lines. A further object is to provide a process and apparatus for forming from an aqueous dispersion of rubber, continuous rubber filaments which are suitable for use in elastic webbing, clothing, etc., as well as for 20 use in other manufactures such as the winding of golf balls.

In the manufacture of rubber filaments by streaming aqueous dispersions of rubber into a coagulating medium, as taught, for instance 25 by the patent to Hopkinson and Gibbons, 1,545,257, granted July 7, 1925, it has been found desirable to accurately determine and control the shape of the filament. For some purposes it is desirable to manufacture a 30 round filament, for others a filament of square cross section, and for others one of rectangular cross section or one which is half round and half flat or semi-circular in cross section. A number of factors enter into the successful 35 production and regulation of such shapes, important among which is the shape of the orifice through which the rubber material is streamed.

I have found that in spinning or forming 40 a filament of a desired cross sectional shape, it is necessary, in order to obtain a preferred cross section, to accurately predetermine the shape of the cross section of the spinnerette or nozzle. For instance, although a square 45 shaped nozzle will form or spin a substantially square filament, especially when a very small orifice is used, the surface tension of the liquid rubber dispersion tends, in the formation of larger filaments, to draw the exposed 50 surface into a shape which presents a

minimum bounding area. Thus the tendency of the surface of a filament formed or spun by streaming through an orifice of any particular shape is to assume the cross sectional contour of a circle, the smallest boundary 55 for the given cross sectional area. In order to counteract this tendency I have devised orifice shapes which vary to some extent from the proposed finished cross sectional contour of the filament to be made, but which so deliver the stream of material that its subsequent tendency to assume a cylindrical shape is utilized to give the exact shape desired.

When an aqueous dispersion of rubber is streamed into a coagulant through a square 60 orifice, the coagulated rubber filament is, as above indicated, slightly different from the cross sectional shape of the orifice, unless the orifice is of extremely small dimensions. Depending upon the particular conditions 65 of formation, the thread may vary from a circular cross section to one having straight sides with rounded corners. Apparently the immediate action of the coagulant is to form a rubber skin at the surface leaving the center 70 in a more or less fluid condition. Immediately after formation, the surface, being still moldable to some extent, exhibits the natural tendency of a tensioned surface to alter its shape to expose the shortest possible boundary 75 over a given area or to present a circular cross-section. Whether the cross-section is round or merely has rounded corners is dependent to some extent on various factors such as the size of the thread, the speed at 80 which it is drawn through the coagulating bath, and the rate of coagulation, all of which affect the rate of coagulation of the center of the thread. The shape of the orifice 85 and the pressure or head under which the material is formed or spun are other factors upon which accuracy and control in result must be based to some extent, as hereinafter indicated.

Figs. 1 and 2 illustrate the contour of an 90 orifice designed to give threads whose cross sectional contours are square and rectangular respectively as shown in Figs. 3 and 4.

Fig. 5 is a sectional view, taken at right angles to Fig. 1. 100

In Fig. 1 an orifice is illustrated as having outwardly concave sides 1 which are provided to merge at the corners into cusps or projecting angles 2, facilitating the production of a square thread like that shown in cross section in Fig. 3. Fig. 2 shows a cross section of an orifice with concave sides 3 and cusps 4 which enables flat thread to be made as indicated in cross section in Fig. 4. When such orifices are used the action of streaming a coagulable liquid into a coagulant is to form a skin at the surface. Surface tension forces then act to reduce the boundaries to a minimum and for a given area the ultimate boundary of a cross section of material will tend to assume the shape of a circle. As the stream leaves the orifice, the shape of the surrounding rubber skin, where an aqueous dispersion of rubber is used, is very closely like that of the orifice. Due to the reduced thickness of the cusps the coagulant penetrates these cusps to a substantial extent and forms relatively rigid corners at these points, after which the sides tend to approach a circular cross-sectional shape so that the sharp projecting angle of the cusp at each corner is widened to a right angle concurrently with the movement of the concave sides as they bulge outwardly. By proper adjustment of the rate of drawing the thread from the nozzle into the coagulant, it is possible to obtain a sufficient depth of coagulation to overcome further changes in cross sectional shape due to surface tension forces and to make the stream sufficiently rigid to hold its own shape at the time that the forces have drawn the surface boundaries into the shape of a square or of a desired figure.

It should be noted that the head or pressure on the streamed liquid and the rate of drawing it away from the nozzle into the coagulant are factors which must be considered in the regulation and control of thread size and shape. For example a high pressure and low rate of pulling will result in the production of a round thread regardless of the shape of the nozzle due to the fact that the surface tension forces have ample time to contract the surface into the form of a circle. With a low pressure and high rate of pulling the coagulant strikes back along the inner surface of the nozzle and more efficiently coagulates the outer layer or surface of the material into a cohesive skin which conforms to the shape of the nozzle. This action is important in an understanding of the present invention and it should be understood that the pressure and rate of pulling should be so adjusted that the material spun through nozzles shaped as herein set out is coagulated at the surface as quickly as possible. The rate of withdrawal may be regulated by varying the speed of the apparatus designed to handle the thread after formation. This may be in the form of a set of

driven rollers or belts upon which the thread is laid or through which it is run. In this manner the rate of coagulation may be altered and such alteration or control may also be accomplished by altering the strength of the coagulating bath. The pressure may be varied by providing a feeding system for the streamed liquid which can be adjusted to give varying pressure heads.

It should be noted that the invention is not only applicable to the production of square and rectangular thread from nozzles of the shape desired, but also can be applied to the production of threads or bands of other shapes bounded by straight lines, for example triangles, parallelograms, polygons, etc. Further by controlling and reducing the rate of drawing the thread from the nozzle and increasing the head under which it is extruded, curved boundaries may be formed instead of straight lines. By the use of longer cusps and more deeply concaved sides a thread may, for example, be produced having small cusps and somewhat concave sides if produced under the same conditions of rate of withdrawal and pressure as described above in the production of square and rectangular material. It should be noted also that the invention is well adapted to the formation of strips, bands or sheets of rubber which may be subsequently cut into desired sizes.

Filaments produced by this invention are more satisfactory for weaving into elastic webbing etc. than round filaments. The sharp, even corners characterizing the square or rectangular thread made in accordance with this invention enables fibrous material to be spun, twisted or wound around the rubber filaments and hold its position thereon, whereas round thread used for the same purpose has been found to allow the fibrous material to slip after twisting or weaving about such rubber filaments. Moreover, round thread is not desirable for certain manufacturers such as golf balls, and by this invention a tough unmilled rubber thread of square or flat cross section may be made which is well adapted to the production of these and other articles.

Rubber thread formed by means of the present invention resists chafing in winding as in the manufacture of golf ball centers and in processing during incorporation in articles such as elastic webbing, and therefore possesses advantages over rubber thread made from crude solid rubber by cutting vulcanized sheets. The latter has ragged corners whereas thread made in accordance with this invention has absolutely smooth and uniform corners.

It is of course understood that vulcanizing agents, accelerators, anti-oxidants, fillers and other compounding ingredients may be added to the aqueous rubber dispersions used and intermixed therewith. After the formation

of rubber articles in accordance with the principles herein set out, they may be dried and vulcanized by any suitable means.

The invention is not limited to the particular embodiment illustrated but is capable of adaptation into various combinations, and sub-combinations, without departing from the principles herein set out.

A suitable apparatus for accomplishing the purposes of this invention is described in a copending application filed by me jointly with Willis A. Gibbons and Alexis W. Keen, Serial No. 521,640, filed concurrently here-with.

Having thus described my invention, what I claim and desire to protect by Letters Patent is:

1. The process of making rubber filaments from an aqueous dispersion of rubber which comprises streaming said dispersion through an orifice having outwardly concave sides and cusped corners.

2. The process of making rubber filaments from an aqueous dispersion of rubber which comprises streaming said dispersion through an orifice having outwardly concave sides and cusped corners at a rate greater than the natural rate of flow of aqueous liquid and under a substantially low pressure head.

3. The process of making rubber filaments from an aqueous dispersion of rubber which comprises streaming said dispersion through orifices having outwardly concave sides and cusped corners while regulating the rate of withdrawal from said orifices.

4. The process of making rubber filaments from aqueous dispersions of rubber which comprises streaming a dispersion through orifices having outwardly concave sides and cusped corners while regulating the rate of withdrawal from said orifices, and the pressure under which such streaming is effected.

5. The process of making rubber filaments from aqueous dispersions of rubber which comprises streaming such a dispersion through orifices having outwardly concave sides and cusped corners, while regulating the pressure under which such streaming is effected, and the rate of coagulation of the streams.

6. The process of making rubber filaments from an aqueous dispersion of rubber which comprises streaming said dispersion into a coagulant through an orifice having outwardly concave sides and projecting cusped corners.

7. The process of making rubber filaments from an aqueous dispersion of rubber which comprises streaming said dispersion into a coagulant through an orifice having outwardly concave sides and cusped corners at a rate greater than the natural rate of flow of the aqueous liquid and under a substantially low pressure head.

8. The process of making rubber filaments

from aqueous dispersions of rubber which comprises streaming such a dispersion into a coagulant through orifices having outwardly concave sides and cusped corners, and then drying said streams and vulcanizing the rubber.

9. The process of making rubber filaments from aqueous dispersions of rubber which comprises streaming such a dispersion into a coagulant through orifices having outwardly concave sides and cusped corners while regulating the rate of withdrawal from said orifices.

10. The process of making rubber filaments from aqueous dispersions of rubber which comprises streaming such a dispersion into a coagulant through orifices having outwardly concave sides and cusped corners while regulating the rate of withdrawal from said orifices, and the pressure under which such streaming is effected.

11. The process of making rubber filaments from aqueous dispersions of rubber which comprises streaming a dispersion into a coagulant through orifices having outwardly concave sides and cusped corners while regulating the pressure under which such streaming is effected and the rate of coagulation of the streams.

12. The process of making rubber filaments from aqueous dispersions of rubber which comprises streaming a dispersion through orifices having outwardly concave sides and cusped corners regulating the pressure under which such streaming is effectuated and the rate of coagulation of the streams, and then drying said streams and vulcanizing the rubber.

13. The process of making rubber filaments from aqueous dispersions of rubber which comprises streaming a dispersion into a coagulant through orifices having outwardly concave sides and cusped corners regulating the pressure under which such streaming is effectuated and the rate of coagulation of the streams, and then drying said streams and vulcanizing the rubber.

14. As a new article of manufacture, a thread forming nozzle for extrusion of aqueous dispersions of rubber having an orifice whose cross section delineates outwardly concave sides and cusped corners.

15. As a new article of manufacture, a thread forming nozzle for extrusion of aqueous dispersions of rubber having an orifice defined by outwardly concave sides and cusped corners, and in which the inner surface of the nozzle adjacent to the orifice is normal to the plane of the orifice.

Signed at Passaic, county of Passaic, State of New Jersey, this 13 day of February 1931.

EARDLEY HAZELL.
